UNITED STATES PATENT OFFICE.

FRANK SCHAFER, OF BARBERTON, OHIO, ASSIGNOR TO THE DIAMOND MATCH COMPANY, OF CHICAGO, ILLINOIS, A CORPORATION OF ILLINOIS.

FEED MECHANISM FOR BOX-SHUCK MACHINES.

1,203,912.

Specification of Letters Patent.

Patented Nov. 7, 1916.

Application filed May 4, 1914. Serial No. 836,108.

To all whom it may concern:

Be it known that I, FRANK SCHAFER, a citizen of the United States, and resident of Barberton, in the county of Summit and State of Ohio, have invented certain new and useful Improvements in Feed Mechanism for Box-Shuck Machines and the like, of which the following is a specification.

This invention relates to improvements in mechanism for feeding paper, card-board, or similar material, to box-making and analogous machines; such improvements being especially though not exclusively designed for use in connection with box-shuck making machines, such, for example, as illustrated in Letters Patent of the United States No. 795,949, dated August 1, 1905.

The object of my invention is to provide a mechanism of the character mentioned of simple and efficient construction and operation whereby sections or blanks, of predetermined length, are severed from a main strip of material, and such sections or blanks then positively fed edgewise in a path at right angles to that of the strip and delivered to the box-forming or other instrumentalities.

My invention consists, primarily, in means for intermittently feeding a strip of material, as taken from a roll, to and across the path of a suitable cutter by means of which successive lengths or sections are severed from the leading end of the strip, and means for engaging the successive lengths or sections as rapidly as they are severed, and positively feeding them edgewise in a path at right angles to that of the strip.

The invention also comprises various features of construction and combinations of parts which will be hereinafter fully described and claimed.

In the drawings—Figure 1 is an end elevation of a feeding mechanism embodying a preferred form of my invention, the mechanism being represented as applied to a box-shuck making machine. Fig. 2 is a plan of Fig. 1. Fig. 3 is a side elevation of the feeding mechanism, and adjuncts. Fig. 4 is a longitudinal vertical section, as on the line 4—4 of Fig. 2. Fig. 5 is a diagrammatic view of the pusher devices for feeding the severed section or blank to the delivery rollers of the shuck machine. In this view the pusher head is represented as about to en-

gage and advance the blank, the path of movement of said head being indicated in dotted outline. Fig. 6 is a similar view showing the parts in relative positions which they occupy during the return movement of the pusher head. Fig. 7 is a diagrammatic view of the device for actuating the feed-rollers for the body of the material, the elements of the device being shown in locking relation to each other. Fig. 8 is a similar view showing the elements in the relative positions which they occupy while actuating the feed-rollers.

10 designates a supporting frame including a bed or table 11. In the lower part of the frame a roll 12 of card-board, or other suitable material, is mounted to rotate. This material is preferably drawn between tension rollers 13 supported in bearings 14 on the frame, and thence under a feed roller 15 on a suitably-driven shaft 16. A friction roller 17 carried by a weighted lever 18 maintains the material in contact with the feed-roller, and the latter in its rotation draws the material at a predetermined speed from the roll and supplies it to a pair of feed rollers 19 arranged above the table. A curved plate 20 for supporting the material as it passes to the feed-rollers 19 is preferably affixed to parallel standards 21 on the table. The shafts 22 of these rollers are mounted in boxes in said standards, the upper boxes being slidably fitted to vertical guides 23 in the standards and being therein depressed by suitably-disposed springs 24 so as to maintain the upper roller in yielding gripping relation to its companion. The roller shafts 22 are equipped with co-acting gear wheels 25 which are intermittently rotated and positively locked during the intervals of rest in such a manner that the rollers feed successive lengths of the material horizontally to and across the path of a vertically-reciprocating cutter 26 whereby definite lengths or sections of the material are severed, as will be hereinafter described.

27 designates a driving shaft which has its bearings in suitably-disposed brackets on the table. Fast on this shaft is a sprocket wheel 28 about which passes a chain 29 actuated from a suitable source of power. The shaft 27 bears a bevel wheel 30 in mesh with a similar wheel 31 on a shaft 32 having its bearings in extensions of the standards,

which latter shaft is provided at one end with a gear wheel 33 in mesh with a similar wheel 34 on a lower stud shaft 35. This stud shaft has fast thereon a sprocket wheel 36 which is connected by means of a chain 38 with a sprocket wheel 37 on the roller shaft 16 above referred to. Thus the shaft 16 and its roller 15 are continuously driven in a manner to supply the material to the feed rollers 19.

Although any suitable means may be employed to actuate and temporarily lock the feed-rollers 19, I have devised and prefer to use for this purpose what may be termed a modified Geneva stop motion of the following character, reference being had to Figs. 1, 2, 7 and 8 of the drawings: 39 designates a spur wheel loosely mounted on a stud shaft projecting outwardly from one of the standards 21, which wheel meshes with the gear 25 of the lower feed roller. On the outer face of this spur wheel are formed four corresponding radial channels 40 disposed at angles of 90° to each other. The walls of each channel are parallel, excepting at their outer ends which are flared or rounded as indicated at 41. Laterally adjacent the channel side of the wheel 39 is another spur wheel 42 which is loosely mounted on a stud-shaft 43 projecting also from the standard 21. This wheel 42 meshes with a pinion 44 on the adjacent outer end of the driven shaft 32, and hence continuous rotary motion is transmitted to the spur wheel 42.

On the inner face of the spur wheel 42 are three projecting tappets 45 comprising studs or rollers which are equally spaced apart at points equidistant from the center of the wheel 42, the spaced relation of the tappets to each other and to the radial channels of the wheel 39 being such that the tappets enter the channels in successive order, move along the same toward the center of the wheel and then recede therefrom, and that as the active tappet in a receding motion approaches the mouth of the channel with which it is engaged the succeeding tappet enters the mouth of the next following channel, and so on.

The curvature of the outer ends of the channels is such that when the wheels 39 and 42 are in the relative positions represented in Figs. 1 and 7 the inner walls of the mouths of the two lower channels are concentric to the wheel 42, that is, such walls comprise corresponding arcs described from the center of that wheel. Hence when both tappets engage and move in the proximate arcuated portions of the channels no motion is transmitted from the continuously rotating wheel 42 to the wheel 39, but on the contrary the latter is temporarily locked against rotation; yet the instant the rearward tappet escapes the mouth of the proximate

channel the leading tappet contacts with and rides upon the opposing radial wall of its channel, progressively entering the latter, as seen in Fig. 8, and then receding therefrom. The three tappets during their continuous rotation thus act in successive order upon the walls of the radial channels to impel and lock the wheel 39; the periods of motion being timed to accomplish the feeding of definite lengths or sections of material successively to and across the path of the cutter and the locking being timely effected and maintained during the periodical actions of the cutter on the material and the removal of the successively severed sections, as will be presently explained.

The mechanical movement just described is simple in construction and smooth and positive in its operation. Owing to the relation of the tappets on the driving element to the channels on the driven element whereby two tappets co-act with the arcuated portions of two channels during the intervals of rest, not only is an effective locking of the driven element insured but the abrupt starting impact inherent in an ordinary Geneva stop motion, is avoided.

The cutter preferably comprises a blade vertically-reciprocable through a suitably-disposed slot in a horizontal shelf 46 upon which the leading end of the material is supported, said shelf being provided with a suitable guide-way 47 in communication with a guide-way which extends at right angles to the path of the advancing material and comprises the shelf and spaced parallel bars 48 thereon. The blade is arranged to reciprocate at the junction of the two guides. It is bolted to a vertically-reciprocating cross-head 49 which is mounted in guides 50 on the standards. This head is provided on one side with a stud or roller 51 which enters the race of a cam 52 fast on the driving shaft 27. The contour of the race or groove of this cam is such that the cutter head is actuated during the idle intervals of the feed rollers 19.

As each section (S, Figs. 2 and 5) is severed from the material such section lies in front of a reciprocative pusher head 53 and is thereby moved through the forwardly-extending guide into engagement with delivery rollers 54, or other conveying means, which are associated with appropriate mechanism for converting the section or blank into box-shucks or other articles. In the present instance, the delivery-rollers 54 of a box-shuck making machine are illustrated, such rollers bearing the usual spaced circumferential scorers 55 for the successive blanks.

The pusher head herein shown is so constructed, supported and operated that in one stroke thereof it impinges against the outer edge of the severed section of the material

and pushes it bodily forward to the bite of the delivery rollers 54, that is, in a path at right angles to that of the main body of the material, and then in the return movement 5 of the head it is lifted over the path of the advancing end of the material and engaged with the outer edge of the next succeeding severed section, and so on. The pusher head comprises a bar provided with two depending 10 pusher pins 56 which are movable into and from suitably disposed slots 57 in the guide structure. (See Fig. 4.) The bar is secured to the upper or free end of one member 58 of an angular feed-frame, the lower 15 or basal end of the other member 59 of which is provided with two oppositely extending arms 60, 61. One (60) of these arms has a wrist-pin connection with a crank-disk 62 on a shaft 63 having its bearings 20 in a bracket 64 extending from the table, and the other arm (61) is pivotally connected to a rocker-arm 65 which is pivoted to brackets 66 on the table. On the shaft 63 is a sprocket wheel 67 which is 25 geared with a similar wheel 68 on the drive shaft 27 by means of a chain 69. By the construction and arrangement just described the crank-disk 62 is continuously driven, the pivotal connection of the arm 30 60 of the angular feed-frame with the disk is rotated about the axis of the latter, and the other arm 61 of the frame is pivotally supported and caused to travel by the rocker-arm 65 in an arc described from the axis of 35 oscillation of said arm 65, the resultant of these motions as translated to the free end of the frame and its pusher head being the movement defined by the dotted lines in Fig. 5.

40 The mechanical movement just described is simple in construction and smooth and positive in its operation. Thereby is avoided the use of a multiplicity of cam and gear connections to accomplish the described com- 45 pound motion of the pusher head.

The hereinbefore described mechanical movements for actuating the feed rollers and the pusher-head respectively, form the subjects of separate applications for patents

filed May 4, 1914 under Serial Nos. 836,109 50 and 836,110, respectively.

I claim—

1. In mechanism of the character described, the combination of means for feeding a strip of material, means for severing 55 succeeding lengths or sections from said strip, and means for directly feeding said lengths or sections edgewise in a path at right angles to that of the strip immediately succeeding the severance of the strip, said 60 last-named means including a reciprocating pusher head the forward and backward strokes of which are through different paths.

2. In mechanism of the character described, the combination of rollers for feeding a strip of material, means for intermittently actuating said rollers, cutter mechanism intersecting the path of the material and adapted to sever succeeding lengths therefrom, a reciprocating pusher head, and 65 means for directly moving the same forward to advance each severed length in a horizontal path at right angles to that of the strip 70 immediately succeeding the severance of the strip and then for returning said head in a 75 different path.

3. In mechanism of the character described, the combination of rollers for feeding a strip of material, means for intermittently actuating said rollers, a guide extending 80 at right angles to and intersecting the path of the strip, said guide having vertical slots extending longitudinally thereof, cutter mechanism adjacent said guide adapted to sever succeeding lengths from the leading 85 end of the strip, a pusher-head for successive lengths movable longitudinally of the guide, said head having depending pins movable relatively to the vertical slots in the guide, and means for actuating said pusher-head. 90

Signed at Barberton in the county of Summit and State of Ohio this 29th day of April A. D. 1914.
